UNITED STATES PATENT OFFICE.

NEWTON K. BOWMAN, OF CANTON, OHIO.

SECTION INSULATOR AND SWITCH.

1,263,028.

Specification of Letters Patent. Patented Apr. 16, 1918.

Application filed March 9, 1917. Serial No. 153,668.

To all whom it may concern:

Be it known that I, NEWTON K. BOWMAN, a citizen of the United States, residing at Canton, in the county of Stark and State of Ohio, have invented certain new and useful Improvements in Section Insulators and Switches, of which the following is a specification.

My invention relates to new and useful improvements in section insulators and hand switches, one object of my invention being the provision of a section insulator and hand switch for trolley wires of the type in which the adjacent ends of trolley wires are clamped in splice sleeves forming part of the body of the insulator so that any slack in the wires may be taken up from time to time without the necessity of cutting the wires.

10 The primary object of my invention, however, consists in the provision of a section insulator and switch of the above type which will insure perfect insulation of the sections when the switch is open and perfect contact when the switch is closed.

20 A further object which I have in view is the provision of a device of this character which will afford a continuous contact for the trolley wheel when the switch is closed and which will insure a safe passage for the trolley wheel in case, through oversight, the switch should not be closed.

30 While keeping these objects in mind, I also aim to construct a section insulator and switch which may be quickly and easily applied, conveniently operated and which is simple and economical in construction, the parts being so arranged as to permit renewal of worn contacts or other parts at small expense.

More specifically, my section insulator and switch includes a pair of splice sleeves to receive ends of an adjacent trolley wire section, the splice sleeves being connected in spaced relation by a block of insulating material and each splice sleeve carrying a switch arm, each having contact plates engageable by the other and the switch arms being connected for simultaneous swinging movement toward and away from each other.

One of the objects of this invention resides in the provision of a novel form of connecting means between the switch arms so that the switch arms will be insulated from each other when in open position, this

means being adjustable to permit taking up of the parts when rendered necessary because of wear.

Another object of the present invention 60 consists in mounting a bridging contact member upon one of the splice sleeves capable of being swung to extend partially beneath the insulating block and provide with the splice sleeves a continuous electric support for a trolley wheel and in providing a novel form of connection between one of the switch arms and this bridging contact, whereby the bridging contact will be moved simultaneously with the switch arms. 65

With these and other objects in view, my invention will be more fully described, illustrated in the accompanying drawings, and then specifically pointed out in the claims which are attached to and form a part of 70 this application.

In the drawings:

Figure 1 is a top plan view of my section insulator and switch in closed position;

Fig. 2 is a corresponding view of the device in open position;

Fig. 3 is a side elevation of the device in closed position;

Fig. 4 is a fragmentary bottom plan view showing features of the switch construction 85 and bridging contact member;

Fig. 5 is a vertical sectional view taken on the line 5—5 of Fig. 3, looking in the direction of the arrows;

Fig. 6 is a perspective view of the splice 90 sleeves and their connection, this figure also showing the bridging contact member in active position.

Corresponding and like parts are referred to in the following description and indicated in all the views of the drawings by the same reference characters.

Broadly speaking, my second insulator and switch primarily includes an intermediate section or bond 10 of insulation, carrying at its ends splice sleeves 11 which in turn carry a switch structure, indicated as a whole by the numeral 12. The intermediate section 10 may be formed of fiber or any other suitable insulating material, being substantially rectangular in cross section with its lower edge plain surfaced. Each of the splice sleeves includes a closed sleeve proper adapted to snugly receive one end of the intermediate section 10 to which it is secured by rivets 13 or other suitable fastening means. Each splice sleeve, beyond this

body portion proper, is cut-away along its upper portion to provide a U-shaped trolley wire receiving portion 14. The bottom wall tapers in thickness adjacent its free end, 5 being reduced externally in order to provide, in connection with a wire extending into the sleeve, as smooth and continuous a bearing surface for the trolley wheel as possible. These splice sleeves, near their outer ends, 10 are formed with upwardly directed opposed ears 15 preferably thickened by exteriorly formed bosses 16 and a rivet, bolt or other suitable fastening device 17 is passed through these ears and forms the pivot for 15 a clamping dog 18. These clamping dogs may be of any suitable type, those shown in the drawings being each in the form of a number of plates of suitable metal, such as steel, having a cam shaped head 19 formed 20 at an eccentric point with an opening for the pivot 17 and at one side with a handle forming shank 20, the free ends of the shanks of all of these sections being loosely secured by a rivet 21 or other fastening device. The peripheral edges of the cam heads 25 of the sections are formed with V-shaped wire engaging teeth 22 in order that the ends of trolley wires passed into the splice sleeves may be firmly clamped in place by 30 swinging the dogs to the positions shown in Fig. 1.

The top of each of the body portions proper of the splice sleeves 11 is formed with an upwardly directed threaded stud 35 23, these studs serving as pivotal supports for the switch structure which will now be explained. A substantially L-shaped switch arm 24 is formed adjacent its bend and upon its upper face with a reinforcing boss 40 25 through which is an opening permitting the mounting of the arm upon one of the studs 23. The upper face of this switch arm is formed throughout the greater portion of its length with a longitudinal reinforcing rib 26 and the arm is held against displacement from the stud by a nut 27. A spring washer 28 is interposed between the boss and nut and is provided with an extension having a notch 29 to engage over 45 this rib 26 to hold the washer against turning movement, the washer in turn anchoring the nut against turning. In like manner, a second substantially L-shaped switch arm 30 is provided, this arm at one end being 50 reinforced by a boss 31 through which is formed an opening to receive the other stud 23 upon which the arm is mounted and secured by a nut 32 and spring washer 33, the washer having a notched extension extending 55 over a longitudinal reinforcing rib 35.

This switch arm 30, adjacent its bend, is formed with an outward extension 36 provided with a strengthening boss 37 and rib 38 and the shorter end of the switch arm 24 60 is also provided with a reinforcing boss 65

39. These bosses are formed with pivot receiving openings and pins 40 are passed through the ends of a link 41 and through the openings of the bosses and anchored against displacement by cotter pins 42 or 70 other suitable fastening devices. This link 41 includes a pair of squared headed bolts 43, each head of which is formed with transverse openings 44 extending at right angles to each other to receive the pins 40 so that 75 either bolt may be released, given a quarter turn and reapplied. The threaded shanks of these bolts engage in the ends of a link 45 of insulating material so that the switch arms are insulated from each other when in 80 open position. The function of this link is to secure simultaneous and reverse movement of the switch arms when either arm is manually moved. As will be seen, the switch arms are mounted to swing one upon either 85 side of the intermediate section of the device and each arm, intermediate its length, has a laterally directed web portion 46, to the upper and lower sides of which are secured opposed resilient contact plates 47, the 90 free ends of which are bent outwardly away from each other somewhat, as shown at 48, in order that the free end of the opposite switch arm may engage snugly between them when the switch is in closed position, as 95 shown in Figs. 1, 3 and 5, the switch arms, together with these contact plates, forming in effect a double knife blade switch to absolutely insure an unrestricted passage of current from one splice sleeve to the other 100 when the switch is closed.

The switch arm 24, adjacent its free end, is formed with an angularly projecting shank 49, the free end of which carries a handle 50. A disk-shaped shield 51, of fiber 105 or other suitable insulating material, is preferably interposed between the handle and shank 46 in order to protect the operator from any possible injury, due to arcing when opening and closing the switch. As 110 will be apparent, this handle projects laterally from the side of the section insulator and switch and may, therefore, be conveniently grasped for opening and closing of the switch, both switch arms moving simultaneously and in opposite directions because of the connecting link 41. The switch arm 24 is preferably provided, as shown in Fig. 3, with a downwardly projecting stop lug 52 adapted to engage the adjacent splice 115 sleeve 11 when the switch is in fully open position.

In order to insure a continuous contact of the trolley wheel when passing the closed switch and in order that the trolley wheel 120 may at no time engage an unenergized portion of the device, I provide a bridging contact member, indicated as a whole by the numeral 53. This member includes an arm 54 pivotally supported by a bolt 55 between 125 130

a pair of vertically spaced ears 56 projecting laterally from the upper portion of that sleeve 11 to which the switch arm 30 is pivoted, the bolt being secured by a nut 57. 5 This arm, at its inner edge and adjacent its free end, is provided with a depending vertical contact plate 58 adapted, in one position, to engage against the adjacent face of the insulating block 10 and provided at its 10 lower edge with a lateral bridging flange 59, the ends of which are cut at opposite angles, as shown at 60 in Fig. 4, in order that the bridging flange may wedge closely between the correspondingly formed ends of the 15 sleeves 11 and so form a true bridge between them. The lower face of this flange should, of course, be rounded, as shown in Fig. 5, to conform to the shaping of the trolley wheel receiving portions of the sleeves. 20 Preferably, the plate portion 58 of the bridging contact member is provided with a lateral reinforcing flange 60. The arm 54 of this contact member is formed with a slot 61 and a pin 62 which may be formed integrally with the arm 30 operates in this slot in such a manner that movement of the switch to closed position will bring the bridging contact member to active position, while when the switch is opened, such member 25 will assume the position shown in Fig. 2. By this means, a continuous energized contact surface is provided for the trolley wheel when the switch is closed.

As will be seen by reference to Fig. 2 of the drawings, ample space is provided for the passage of a trolley wheel when the switch is opened so that no injury will be caused either to the trolley wheel or to the switch arms, in case the switch should be 30 left open through oversight. Inasmuch as my section insulator and switch is extremely simple in construction, its operation will be readily appreciated by referring to the drawings and no further explanation is believed to be necessary. All arcing at the switch during the passage of a trolley wheel is prevented as the wheel at no time engages an unenergized portion of the device.

Although I have illustrated and described 35 my invention in all its details of construction, it will of course be understood that I reserve the right to make any changes, within the scope of the appended claims, which may be found desirable, without in 40 the slightest degree departing from the spirit of my invention.

Having thus described the invention, what is claimed as new is:

1. A section insulator and switch including an intermediate body of insulating material, wire receiving splice sleeves carried by the body and insulated from each other thereby, switch arms mounted upon the sleeves and each having a contact plate 45 engageable by the other switch arm in one

position of the arms, and an adjustable insulating connection between the switch arms whereby they will swing in unison.

2. A section insulator and switch including an intermediate body of insulating material, 70 wire receiving splice sleeves carried by the body and insulated from each other thereby, switch arms mounted upon the sleeves and each having a contact plate engageable by the other switch arm in one position of the 75 arms, and an adjustable insulating connection between the switch arms whereby they will swing in unison, said connection including a link of insulating material, bolts threaded into the ends of the link and having heads formed with openings, and pins inserted through the openings and engaging in the switch arms.

3. A section insulator and switch including trolley wire receiving splice sleeves, a 85 member of insulating material connecting the splice sleeves, switch arms swingingly mounted upon the splice sleeves and movable toward and away from each other to close and open a circuit between the splice sleeves, 90 means for manually swinging one of the switch arms, and an insulating adjustable connection between the switch arms.

4. A section insulator and switch including trolley wire receiving splice sleeves, a 95 member of insulating material connecting the splice sleeves, switch arms swingingly mounted upon the splice sleeves and movable toward and away from each other to open and close a circuit between the splice sleeves, 100 means swingingly carried by one of the splice sleeves for bridging the gap between the adjacent ends of the splice sleeves to afford a continuous electrical contact for a trolley passing the switch when the latter 105 is closed, and connecting means between one of the switch arms and said bridging means whereby the bridging means will be brought to active position when the switch is closed.

5. A section insulator and switch including trolley wire receiving splice sleeves, a member of insulating material connecting the splice sleeves, switch arms swingingly mounted upon the splice sleeves and movable toward and away from each other to open 110 and close a circuit between the splice sleeves, means swingingly carried by one of the splice sleeves for bridging gap between the adjacent ends of the splice sleeves to afford a continuous electrical contact for a trolley 115 passing the switch when the latter is closed, and connecting means between one of the switch arms and said bridging means whereby the bridging means will be brought to active position when the switch is closed, said 120 connecting means including an element projecting from one of the switch arms and operating in a slot formed in the bridging means.

6. A section insulator and switch includ- 130

1
ing trolley wire receiving splice sleeves, a member of insulating material connecting the splice sleeves, an arm pivoted to one of the splice sleeves and having a depending 5 plate portion carrying at its lower edge a bridging flange adapted to seat closely between the ends of the splice sleeves and against the lower portion of the member of insulating material in one position of the 10 arm, switch arms swingingly mounted upon the splice sleeves and movable toward and away from each other to open and close a circuit between the sleeves, and operative connection between one of the switch arms 15 and the first mentioned arm.

7. A section insulator and switch including trolley wire receiving splice sleeves, a member of insulating material connecting the splice sleeves, an arm pivoted to one of the splice sleeves and having a depending 20 plate portion carrying at its lower edge a bridging flange adapted to seat closely be-

tween the ends of the splice sleeves and against the lower portion of the member of insulating material in one position of the 25 arm, switch arms swingingly mounted upon the splice sleeves and movable toward and away from each other to open and close a circuit between the sleeves, and pin and slot connection between one of the switch arms 30 and the first mentioned arm.

8. A section insulator and switch including trolley wire receiving splice sleeves, a member of insulating material connecting the splice sleeves, switch arms simultaneously movable to engage each other and electrically connect the splice sleeves and a bridging member operated by one switch arm and adapted when the switch arms engage each other to engage between the splice sleeves 40 to provide with them a continuous electrical contact for a trolley wheel.

In testimony whereof I affix my signature.
NEWTON K. BOWMAN. [L. s.]
